(57) **CLAIM**

The ornamental design for a jewelry cuff, as shown and described.

DESCRIPTION

FIG. 1 is a front perspective view of a jewelry cuff showing my new design;

FIG. 2 is a front view of the jewelry cuff shown in FIG. 1; FIG. 3 is a rear view of the jewelry cuff shown in FIG. 1; FIG. 4 is a left side view of the jewelry cuff shown in FIG. 1;

FIG. 5 is a right side view of the jewelry cuff shown in FIG. 1;

FIG. 6 is a top view of the jewelry cuff shown in FIG. 1; FIG. 7 is a bottom view of the jewelry cuff shown in FIG. 1; and,

FIG. 8 is a bottom perspective view of the jewelry cuff shown in FIG. 1.

The broken lines depicting the hinge, pin, and portions of the jewelry cuff show unclaimed subject matter and form no part of the claimed design.

1 Claim, 6 Drawing Sheets
